CLAIM

The ornamental design for an actuator button with textured surface as shown and described.

DESCRIPTION

FIG. 1 is a perspective view of an actuator button with textured surface showing the new design.

FIG. 2 is a front view thereof.

FIG. 3 is rear view thereof.

FIG. 4 is a right-side view thereof.

FIG. 5 is a left-side view thereof.

FIG. 6 is a top view thereof.

FIG. 7 is a bottom view thereof.

FIG. 8 is an enlarged perspective view thereof; and,

FIG. 9 is an enlarged front view thereof.

In these drawings, the solid lines illustrate the claimed ornamental design, whereas broken lines, if present, illustrate unclaimed subject matter and form no part of the claimed design.

1 Claim, 9 Drawing Sheets(56)
